UNITED STATES PATENT OFFICE

2,121,466

SCALP PROTECTING PAD FOR HAIR
WAVING

Vito Geraci, Brooklyn, N. Y., assignor of one-half to Alfonso Furibondo, Brooklyn, N. Y.

Application March 30, 1937, Serial No. 133,786

5 Claims. (Cl. 132—36.1)

The invention relates to pads used for protecting the scalp of persons having their hair waved, and it is particularly well adapted for use with the so-called "Croquignole system" of permanent waving. It has for its main object to so construct the pad that it will positively prevent undue heating of the scalp, as well as eliminate any danger from scalding by the hot vapor or steam created during the process.

Another object is to provide a pad of sanitary construction which can be thoroughly cleaned after use. Additional objects are to provide a pad of this type which is easy to manipulate, which will hold the strands of hair from going astray without any extra effort on the part of the operator, and which can be manufactured and sold at a relatively low cost.

These and various other objects and advantages will be readily understood from the following description and from the accompanying drawing of a preferred embodiment of the invention, in which, however, certain modifications might be made without departing from the scope of the appended claims. In the drawing,

Fig. 1 is a plan view of the pad,

Fig. 2 is a similar plan view but with the flaps turned up,

Fig. 3 is a side view of Fig. 1,

Fig. 4 is a side view of Fig. 2,

Fig. 5 is a plan view showing the pad with a clamp attached, and

Fig. 6 is a side view of Fig. 5.

Referring now to all the views simultaneously, the device consists of a pad 10, preferably made of felt in which a slit 11 is cut. A piece of sheet rubber, or other, preferably water-proof, material is placed on top of the felt pad. This sheet is provided with a central slot 12 and with a plurality of slits 13 so that two flaps 14 and 15 are formed as well as two supporting members 16 and 17. The supporting members 16 and 17 are stitched, glued or otherwise secured on top of the felt pad in such a manner that the slit 11 in the felt is exactly in the center of the slot 12.

By constructing the pad in this manner the flaps 14 and 15 may be bent upwardly, as plainly shown in Figs. 2, 4 and 6 and be inserted between the jaws of any standard clamp 18, such as are generally used in hair waving. The pad is used in the following manner: A strand of hair to be waved is drawn through the slit 11 and through the slot 12 until the pad 10 rests upon the scalp of the person being treated. The flaps 14 and 15 are now raised after which the clamp 18 is fastened around the flaps and tightened in the

usual manner. The clamp rests on the supporting members 16 and 17.

In folding up the flaps, air passages 19 are formed between the bottom of the flaps and the felt pad 10. It will be seen that, when in place, the strands of hair are embedded in the soft rubber flaps and that no steam from the waving operation can possibly penetrate between the flaps and thus injure the scalp. Furthermore, the ends of the slot 12 effectively prevent the hairs from being dislodged.

The advantage of having the flaps foldable, as shown, is that it makes it much easier to draw the strands of hair through the pad and arrange it properly for treatment. Furthermore, the hair can be clamped much tighter than would be the case if the flaps were formed integrally with the pad, as has been previously done. In addition to this it makes it much easier to clean the pad after it has been used, as well as to store it. While the hair is being treated currents of air can freely pass through the air openings 19, thus tending to cool the scalp. It will be noted that inasmuch as the clamp 18 rests on the members 16 and 17 it does not interfere with these openings.

Having described the invention and its objects, what I claim as new and wish to protect by Letters Patent is:—

1. A scalp protecting pad, of the class described, comprising a sheet of water proof material having a substantially centrally located slot; two cuts provided in each side of the water proof sheet so as to form two oppositely-disposed flaps; the ends of the sheet secured to the top of a soft, heat-insulating pad having a slit aligned with the slot in the sheet; the pad adapted to rest on the scalp of the person having his hair waved; the slit in the pad adapted to have a lock of hair passed through it; and the flaps of the sheet adapted to be folded up to engage the lock of hair with their inner faces and to be engaged on their outer faces by the clamp customarily used in hair waving.

2. A scalp protecting pad, of the class described, comprising a sheet of water proof material having a substantially centrally located slot; two cuts provided in each side of the water proof sheet so as to form two oppositely-disposed flaps; the ends of the sheet secured to the top of a soft, heat-insulating pad having a slit aligned with the slot in the sheet; the pad adapted to rest on the scalp of the person having his hair waved; the slit in the pad adapted to have a lock of hair passed through it; the flaps of the sheet

adapted to be folded up to engage the lock of hair with their inner faces and to be engaged on their outer faces by the clamp customarily used in hair waving; and the cuts which form the flaps made of such length that the material between the oppositely-disposed cuts will be shorter than the width of the slot in the sheet so that, when the flaps are turned up, air passages will be formed between the lower edges of these and the top of the heat insulating pad; and the ends of the sheet adapted to support said clamp to raise it above the pad so as to not interfere with the air passages.

5. A scalp protecting pad, of the class described, comprising a sheet of water proof material having a substantially centrally located slot; two cuts provided in each side of the water proof sheet so as to form two oppositely-disposed flaps; the ends of the sheet secured to the top of a soft, heat-insulating pad having a slit aligned with the slot in the sheet; the pad adapted to rest on the scalp of the person having his hair waved; 10 the slit in the pad adapted to have a lock of hair passed through it; the flaps of the sheet adapted to be folded up to engage the lock of hair with their inner faces and to be engaged on their outer faces by the clamp customarily used in hair waving; the cuts which form the flaps made of such length that the material between the oppositely-

disposed cuts will be shorter than the width of the slot in the sheet so that, when the flaps are turned up, air passages will be formed between the lower edges of these and the top of the heat insulating pad; and the ends of the sheet adapted to support said clamp to raise it above the pad so as to not interfere with the air passages.

4. A scalp protecting pad, of the class described, comprising a sheet of material having a substantially centrally located slot; a flap formed integrally with the sheet on each side of the slot; and said flaps adapted to lie down flat and to be folded up to engage a lock of hair with their inner faces and to be engaged on their outer faces by a clamp of the kind customarily used in hair 15 waving.

5. A scalp protecting pad, of the class described, comprising a sheet of material having a substantially centrally located slot; two cuts provided in each side of the sheet so as to form two oppositely-disposed flaps; and said flaps adapted to lie down flat and to be folded up to engage a lock of hair with their inner faces and to be engaged on their outer faces by a clamp of the kind customarily used in hair waving.

25 VITO GERACI.
